UNITED STATES PATENT OFFICE.

THADDEUS A. NOLAN, OF CINCINNATI, OHIO.

MAGAZINE FOR PICTURE-FILMS.

No. 921,274.

Specification of Letters Patent. Patented May 11, 1909.

Application filed January 2, 1899. Serial No. 470,440.

To all whom it may concern:

Be it known that I, THADDEUS A. NOLAN, a citizen of the United States, residing in Cincinnati, county of Hamilton, and State of Ohio, have invented certain new and useful Improvements in Magazines for Picture-Films, of which the following is a full, clear, and exact description, reference being had to the accompanying drawings, forming part of this specification.

The film for moving picture machines is usually mounted on a reel suitably journaled in a box or receptacle, so as to feed the picture film at a rapid and constant rate of speed to the machine. These films in addition to being dry and exceedingly fragile, are also highly inflammable, and under the concentrated rays from the lantern very readily take fire.

In magazines as heretofore constructed, the reel carrying the film is mounted in a metal box, provided with a lid for access thereto, and it frequently happens that when the film is in use the lid is carelessly left open, or so negligently closed that it will open accidentally, and as a result, notwithstanding the devices that may be employed to prevent the exposed portion of the film if accidentally ignited, from carrying the flame back into the magazine, and thus destroying the entire film, and becoming a serious menace to the building in which the pictures are being exhibited, such protecting devices are of no avail.

It is the chief purpose of my invention to overcome this difficulty, by that novel construction to be hereinafter pointed out and claimed, whereby it shall be impossible to operate the device, and to feed the film from the box to the point of exposure, unless the box is closed. The moment the magazine is opened, the delivery opening in the magazine is thrown out of alignment with the feed device for the film, so that the film cannot be fed from the magazine while exposed to the lantern rays while the box is open. It is also the object of my invention to provide means for surrounding the reel in the magazine with dampened absorbent material, to render the film moist and pliable and less inflammable, and I also provide means to prevent any flame entering the magazine through the feed opening for the film, when the film is in use.

In the drawings Figure 1 is a perspective view of my improved construction with the

magazine open. Fig. 2 is a perspective view of the magazine closed. Fig. 3 is a central vertical section of the magazine, as shown in Fig. 2.

1 is a portion of the picture film machine, provided with the feed roller 2, and tension roller 3, by means of which the film is fed to the machine.

4 is the bracket secured in any convenient way, as by a thumb screw 5 to the frame of the machine. Rigidly secured to this bracket 4, is the fixed member 6 of the magazine for holding the reel upon which the picture film is mounted.

7 is the hinged member forming with the fixed member, a metal box or case. This hinged member is comparatively deep flanged to form a compartment for holding the reel 9, upon which the picture film is mounted, the reel being journaled on a spindle 10, secured to the back of the hinged member. The fixed member 6 is provided with flanges 11, to fit down over the flanges of the hinged member to form a tight inclosure.

The interior of the compartment for holding the reel is provided with a wire gauze partition 12, encircling the reel, and the space outside of this partition is provided with hinged lids 13, 13, preferably flanged to come down over the edge of the wire gauze and 14, 14 are spring catches to hold these lids shut. Within this space encircling the reel, are placed sponges or other absorbent material 15, properly dampened with water to lace with moisture the atmosphere within the case when the magazine is closed.

16 is a slotted opening in the side wall of the hinged member, at which opening are mounted metal rollers 17, 17, and between which rollers the film is passed, these rollers completely filling up the slot in the case, but with such narrow space between them, that the heat is rapidly conducted away, and any flame from the film which may have been ignited outside the case cannot advance to the film mounted on the reel.

18 is any convenient clasp for holding the magazine closed.

It will be evident from the foregoing description that when the magazine is mounted on the picture frame machine, and the picture film from the reel is fed to the feeding devices of the machine, that if any attempt is made to open the case, whether accidentally or otherwise, or if the case is not closed, the film will be at once fractured and broken.

as the feed opening through the case will be thrown out of alignment with the feeding devices of the machine. 25

It will also be evident that when the magazine is closed, there will be no opportunity 5 for a flame to enter the magazine and destroy the film on the reel.

Having thus described my invention what I claim as new and desire to secure by Letters 10 Patent, is:

1. In a device of the character specified, in combination with the frame and feeding devices of a picture machine, a magazine comprising a relatively fixed member and a hinged member forming a metal case, a reel 15 for the picture film journaled on the hinged member, and said hinged member provided with an opening for the passage of the film.

2. In a device of the character specified, 20 in combination with the frame and feeding devices of a picture machine, a magazine comprising a relatively fixed member and a hinged member forming a metal case, a reel for the picture film journaled on the hinged

member, and said hinged member provided 25 with an opening for the passage of the film, with metal rollers mounted in said opening to close same and between which rollers the film passes.

3. In a device of the character specified, 30 in combination with the frame and feeding devices of a picture machine, a magazine comprising a relatively fixed member and a hinged member forming a metal case, a reel 35 for the picture film journaled on the hinged member, and said hinged member provided with an opening for the passage of the film, with metal rollers mounted in said opening to close same and between which rollers the film passes, and a separate receptacle surrounding said reel with absorbent material 40 therein to render the atmosphere moist within the case, when the magazine is closed.

THADDEUS A. NOLAN.
